UNITED STATES PATENT OFFICE.

JOHN FRICK, OF PHILADELPHIA, PENNSYLVANIA, ASSIGNOR TO FRICK AND SCHLOSSER COMPANY, OF PHILADELPHIA, PENNSYLVANIA, A CORPORATION OF DELAWARE.

COIN-CONTROLLED DISPENSING MACHINE.

1,356,350.

Specification of Letters Patent. Patented Oct. 19, 1920.

Original application filed December 3, 1919, Serial No. 342,161. Divided and this application filed May 20, 1920. Serial No. 382,701.

To all whom it may concern:

Be it known that I, JOHN FRICK, a citizen of the United States, residing at Philadelphia, county of Philadelphia, and State of Pennsylvania, have invented a new and useful Improvement in Coin-Controlled Dispensing-Machines, of which the following is a full, clear, and exact description, reference being had to the accompanying drawings, which form a part of this specification.

The object of my invention is to provide an improved form of coin-controlled dispensing device adapted to deliver successive portions of food or other articles upon the insertion of a coin or a predetermined number of coins totaling the amount to be collected.

Referring to the accompanying drawings, in which I have illustrated a preferred embodiment of my invention and in which like symbols refer to like parts in the various views—

Figure 1 is a side elevation of the delivery shelves.

Fig. 2 is a front elevation of the delivery shelves.

Fig. 3 is a detailed view, partly in section, of the actuating mechanism.

Fig. 4 is a view on line 4—4 Fig. 3.

Fig. 5 is a horizontal section through the machine.

Fig. 6 is a side elevation of the machine, partly in section.

Upon the base *a* and within a casing *b* is mounted an inclosed shaft or chamber having a front wall *c* of glass let into the casing and provided with an aperture at its lower end adjacent the base. The side walls are formed from solid pieces *e*, while the rear is closed by a door *f*. A dumb waiter, comprising shelves *h* (the lower one of which is provided with an apron *i*) secured between uprights *j*, is adapted to work up and down in the shaft, the uprights being guided by pieces *k*. A series of cams *l*, *l'* are secured to the outside of one of the uprights *j*.

A hand lever *m* extends through the casing and is pivoted to a bracket *n* secured to the inside of the casing. The lower arm of the lever is connected to one end of a hollow plunger *o*, adapted to slide horizon-

tally in a bearing *p*, by means of a slot and pin connection. A spring *g* returns and retains the handle in normal position. A rod *q* on a line with plunger *o*, but normally spaced therefrom, is supported by and adapted to slide in a bearing *r*. One end of the rod *q* is pivotally connected to a link *s*, the other end of which is pivoted to an arm *t*, the pivot pin carrying a roller *u* adapted to underlie one of the cams *l*, as shown in Fig. 4. The other end of arm *t* is pivoted to a bracket *v*. A hanger *w*, provided with a series of holes *x* adapted to carry a pin *y* which in normal position enters one of the holes *z* in the wall of a chute *2* and blocks or stops the chute, is secured to rod *q* by means of a set screw and depends therefrom, its lower end being guided by a guide slot. A link 10 pivoted to the lever *m* is connected to the hanger adjacent rod *q* by a slot and pin connection.

A coin slot *3*, in the casing, communicates with a chute *5* adapted to easily carry a coin of predetermined size and is provided, on its under side, with apertures *6*, just narrower than the coin for which the chute is adapted. The cover of the chute is provided with holes *7* for inspection purposes and for extracting any coin which might become jammed. The lower end of the chute opens above the space between the end of the hollow plunger *o* and the end of the rod *q* and directly over chute *2*.

An opening is provided in the base *a* beneath chute *2*, communicating with a coin box *9*.

The open end of plunger *o* is magnetized to divert any slugs or fake coins from chute *2*, as indicated at 11, causing them to drop directly into the coin box and not form a connection for the actuating mechanism.

In operation, the dumb waiter shelves *h* are supplied, through door *f* at the back, with the article to be dispensed and the dumb waiter raised to its upper position, where it is maintained by the engagement 100 of roller *u* with the under side of the lower cam *l*, there being a pair of cams *l*, *l'* for each shelf.

The machine may be set to vend the articles for any number of coins, the amount 105 charged determining the number, as, for ex-

ample, if the price of the articles is ten cents, the pin y is inserted in the second series of holes x, z in the hanger w and wall of chute 2 and acts as a stop in chute 2, as shown in Fig. 3, so that the mechanism will not become operative until two nickels have been deposited.

To operate the mechanism, a nickel is inserted in the slot and travels down the chute 10 5 between the ends of plunger o and rod q , into chute 2, resting on the pin y , the pin being set as in Fig. 3. A second nickel is deposited and comes to rest on top of the first squarely between plunger o and rod q . 15 The hand lever m is then depressed, causing the plunger o to move forward and engage the nickel between its end and the end of rod q . Continued movement causes rod q to move, which movement is conveyed to 20 roller u through link s and arm t , causing the roller to move toward the point of cam l . The hanger w moves with the rod q causing pin y to be withdrawn from chute 2 and permitting the coin or coins in the chute to 25 drop through the opening in the base a into a coin box 9. As the roller u reaches the point of cam l , the plunger o is stopped by contacting with the edge of the bearing r . The weight of the dumb waiter trips the 30 roller off the point of the cam, giving the rod q a slight independent motion which releases the coin forming the connection between plunger o and rod q and permits it to drop through the opening in the base into 35 box 9. The dumb waiter descends under its own weight and cam l' strikes the roller, forcing it back under the next cam l , which it engages, stopping the waiter with the first shelf h flush with the lower edge of 40 aperture d in the front of the shaft through which the articles on the shelf may be withdrawn. The backward movement of roller u is transmitted to rod q through link s and arm t , causing rod q to move backward; and 45 the coin forming connection between plunger o and rod q having been released, it telescopes within plunger o . The handle, being released, is brought back to normal by means of spring g . This movement of the 50 handle, through link 10, causes hanger w to return to normal, with pin y extending into chute 2.

The apparatus is then in position to repeat and bring all of the shelves h opposite 55 the aperture in the front of the shaft, successively.

It will be obvious that the number of coins required to operate the mechanism may be changed and regulated by the positions of 60 pin y .

Should any fake coins be inserted in the apparatus, as, for example, slugs or washers having central holes, the actuating mechanism will not be connected since the end of 65 rod q is of a size to penetrate such holes and

depression of lever m would result merely in telescoping of the rod in plunger o . The magnetized end of plunger o will divert any magnetizable slugs and prevent them from entering chute 2. The diverted slugs will 70 drop through the mechanism as shown at 11, and fall outside of chute 2, directly into the coin box. The chute 5 will not accommodate coins larger than the predetermined size and smaller coins will drop out of the 75 chute through apertures 6 in the under side of the chute.

I do not herein claim the details of the coin-controlled apparatus, as the same forms the subject-matter of an application filed 80 by me December 3, 1919, Serial No. 342,161, of which this application is a division.

Having now fully described my invention, what I claim and desire to protect by Letters Patent is:—

1. In a coin-controlled dispensing machine, the combination with a dumb waiter, of a member having a groove and a plurality of stop seats, a spring actuated stop within the groove adapted to arrest the descent of the waiter at a number of different vertical positions when in engagement with either of said seats and also movable out of supporting relation therewith to allow it to descend from one vertical position to another, means to withdraw the stop out of said supporting relation, manually-operable mechanism, a coin receiver adapted to receive and so position a coin that the coin acts, in the operation of said mechanism, to form an operative connecting link between said mechanism and the stop-withdrawal means, and cams on the grooved member to shift the stop against the action of its spring to permit the dumb waiter to be freely raised. 1

2. In a coin-controlled dispensing machine, the combination with a dumb waiter, a series of projections thereon and a series of cams thereon, of a stop normally engaging one of said projections and thereby holding the waiter from descent, coin-controlled and manually-operable means to displace said stop from supporting position, said stop being movable by one of said cams, in the descent of the released waiter, into position to engage the next projection and thereby arrest the descent of the waiter.

3. In a coin-controlled dispensing machine, the combination with a dumb waiter, of a series of projections thereon arranged one above another, a series of cams thereon arranged in staggered relation with the projections and providing a zig-zag path for the stop hereinafter mentioned, a pivoted stop normally extending under a projection to support the waiter, coin-controlled and manually-operable means to swing said stop from under a projection and into the path of the cam immediately above it, said cam, in the descent of the waiter, swinging the

stop back into position into the path of the next projection of the series.

4. A device of the character described comprising a cam member with a race having a plurality of stop seats in spaced relation, and a spring actuated movable stop within said race arranged to arrest the movement of the cam in one direction when the stop is in engagement with any of the cams in the cam member seats, said race being shaped to permit the stop to move freely in the reverse direction and shift the stop against the action of its spring during such movement.
5. In a coin-controlled dispensing machine, the combination with a dumb waiter, of a series of projections thereon arranged one above another, a series of cams thereon arranged in staggered relation with the projections and providing a zig-zag path for

the stop hereinafter mentioned, a pivoted stop normally extending under a projection to support the waiter, coin-controlled and manually-operable means to swing said stop from under a projection and into the path 25 of the cam immediately above it, said cam, in the descent of the waiter, swinging the stop back into position into the path of the next projection of the series; the cams and the projections are provided with upper 30 cam faces, thus allowing the waiter to be freely raised and in the course of its ascent causing the stop to vibrate back and forth until it settles beneath the lower projection of the series.

In testimony of which invention, I have hereunto set my hand, at Philadelphia, Pa., on this 14th day of May, 1920.

JOHN FRICK.
